MODULAR DESK

George M. Morris, 3900 Circle Drive,
Independence, Mo. 64052

Filed Jan. 10, 1972, Ser. No. 216,911

Term of patent 14 years

Int. Cl. D6—04

U.S. Cl. D6—159

Fig. 1.

Fig. 2.

Fig. 3.

*Fig. 4.**Fig. 5.**Fig. 6.*

FIG. 1 is a top plan view of a modular desk showing my new design;

FIG. 2 is a front elevational view;

FIG. 3 is a rear elevational view;

FIG. 4 is a left side elevational view, the opposite side being a mirror image thereof;

FIG. 5 is a sectional view taken along line 5-5 of FIG. 2; and

FIG. 6 is a sectional view taken along line 6-6 of FIG. 2.

I claim:

The ornamental design for a modular desk, as shown.
